Primary Examiner — Catherine R Oliver-Garcia(74) *Attorney, Agent, or Firm* — LegalForce RAPC Worldwide(57) **CLAIM**

The ornamental design for a telescopic flyswatter, as shown and described.

DESCRIPTION

FIG. 1 is a front left side perspective view for a telescopic flyswatter, showing our new design;

FIG. 2 is a rear right side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof, the right side elevational view being a mirror image; and,

FIG. 6 is a rear right side perspective view of telescopic flyswatter, with handle in extended configuration thereof.
